UNITED STATES PATENT OFFICE

IRVING T. BENNETT, OF BROOKLYN, NEW YORK, ASSIGNOR, BY MESNE ASSIGNMENTS,
TO AMERICAN RADIATOR & STANDARD SANITARY CORPORATION, A CORPORA-
TION OF DELAWARE

RADIATOR

Application filed September 12, 1928. Serial No. 305,337.

My invention aims to provide improvements in radiators operating chiefly by convection so as to circulate the warm air rapidly and uniformly throughout a room. Or the 5 apparatus may be used for cooling by supplying it with cold brine or the like instead of steam or other heating medium.

The accompanying drawings illustrate embodiments of the invention.

- 10 Fig. 1 is a plan;
Fig. 2 is a face elevation;
Fig. 3 is an end elevation of a radiator;
Fig. 4 is a vertical section on the line 4—4 of Fig. 2;
15 Fig. 5 is a front elevation of the chamber for the heating medium;
Figs. 6, 7, 8, 9 and 10 are sectional views similar to Fig. 4 illustrating alternative chambers;
20 Fig. 11 is a partial section similar to Fig. 4 illustrating an alternative style of construction;
Fig. 12 is a section similar to Fig. 4 illustrating another modification.

25 In certain previous Patents 1,774,078, January 21, 1930 to Thomas E. Murray and No. 1,713,459, June 11, 1929 to Murray & Phelps, there are described radiators comprising a heating element with an extended surface 30 structure applied thereto for conducting the heat away from the heating element rapidly and transmitting it to the air circulating upward in flues and open ducts formed by said structure; and with this style of radiators a 35 high degree of efficiency has been achieved.

The preferred metal has been copper for its superior conductivity, and the heating elements described in said applications have been tubes or other thin walled chambers. 40 When tubes are used their shape gives them considerable strength against collapsing under an internal vacuum as well as against distortion under pressure from within.

When a non-circular chamber has been 45 used, the flexibility of the thin side walls has necessitated the designing of the rest of the structure so as to stiffen them against substantial distortion under either pressure or vacuum within.

50 An important feature of the present con-

struction is the use of a chamber of slight width compared to its height but which nevertheless is substantially rigid and capable of resisting the pressure occurring in use. Such a chamber has the advantage that 55 it provides a great surface to which the extended area structure can be joined, thus providing a very wide path for transmission of the heat from the heating element to said structure.

Referring to Fig. 1, the heating element, or prime surface, is formed by a narrow chamber or vessel 1 which may be less than an inch in width from front to back and which has a height many times its width. It therefore 60 has a large inside heating surface for contact with the steam or other heating medium as well as a large external surface for transmitting heat. Because of the large surface utilized it need not be of copper but may be of 65 less expensive materials such as cast iron; though it may also be of other metals such as other kinds of iron or steel, cooper, brass, aluminum or alloys thereof, or in fact almost any metal.

It is made with enlarged circular bosses 2 at the four corners, which may be drilled and tapped for pipe connections as desired. Different combinations will be best for different 70 locations.

In the case illustrated the upper left-hand and the lower right-hand projections are drilled for an admission and an outlet pipe respectively. Rigidity is secured with comparatively thin walls by making the casting 75 with internal cross webs at intervals such as the cylindrical webs 3 so located that the internal pressure on a given area shall always be well within the bursting strength of the casting. Where cast iron or similar metal is used, the front and back surfaces will be faced or machined so as to improve the external contact with the extended area structure.

On the face of the chamber there is applied a radiating structure comprising transverse fins 4 with longitudinal webs 5 connecting them in successive pairs at their outer edges and with alternately located inner plates 6 100

connecting their inner edges as shown in Fig. 1.

This structure is conveniently made up of corrugated sheets either extending in one piece from end to end of the radiator, or made up in units of less length. When applied they form a number of vertical flues 7 which are closed in cross-section and alternate ducts 8 which are closed at the sides and inner ends 10 but open at the outer ends. Through these flues and ducts, open at top and bottom, the air circulates and is heated by contact with their extended area so that its velocity is accelerated and it is circulated rapidly through- 15 out the room. The design of these flues and ducts is such that practically all the heat energy is transmitted by the convection principle and only a very small part of the total heat output is radiant energy. In the circu- 20 lating effect the closed flues 7 are more efficient than the open ducts 8; though both styles of passage have a substantial effect in creating a draft and circulating the warmed air through a room.

25 The fins 4 are inclined in alternately opposite directions so as to provide flared open spaces 8 which facilitate the insertion of fastening means. The plates 6 are applied to the heating chamber with a close heat con- 30 ducting connection throughout their length and width. This may be done by soldering, welding, brazing or the like. Preferably, however, separate fastening members are used, as illustrated. These may be in the 35 form of channels with longitudinal webs 9 and transverse flanges or fins 10. The corrugated structure and the straps or fastening members extend above and below the heating chamber, where they are drawn closely 40 against the heating chamber by means of screws 11.

The extended area structure is preferably of copper, in which term I include cuprous metals generally, and the straps of steel (in which I include ferrous metal generally). The copper may be used in very thin sheets, the steel straps serving to contribute stiffness and being generally slightly heavier. The flanges 10 may be made of greater width so 45 as to provide additional area for contact with the air. In that case the spaces between the closed flues may be made wider. Instead of copper, other materials may be successfully employed; such as aluminum, brass, zinc, steel and, in fact, any workable metal.

Various other methods may be used for securing the fins to the steam chamber. Fig. 11 illustrates an alternate method. The webs 9 of the straps are bent inward immediately above the chamber, the plates 6 being cut away to permit the bringing of the ends 12 close to each other. They are then forced together and connected by welds 13. This may be made in various ways, or screws, rivets or the like may be used.

The circulating passages formed by the extended area structure may be carried to a height considerably greater than that of the chamber, as in Fig. 12, so as to effect the full- 70 est utilization of the heat. This is partic- 75 ularly useful in using steam at the highest temperatures. The increased height of these passages provides, of course, an increased air- 80 heating area as well as an increased rate of circulation.

The chamber 14 in this case is made of less height than in the previous figures. The fins and straps are connected by screws 11 im- 85 mediately above and below the chamber and in addition by screw 15 near the upper end 90 passing through tubular spacers 16.

The desired rigidity of the chamber may be achieved without using a casting therefor. Figs. 6 to 10 illustrate the use of sheet steel of heavy gage, say one-eighth of an inch or 95 heavier. According to Fig. 6 a single sheet 17 is used with its edges 18 and 19 overlapping and soldered, welded, brazed or other- 100 wise made steam-tight. This chamber as well as those of the other figures may be re- 105inforced internally by longitudinal channels 20 welded in place and having flanges 21 spanning the width between the walls so as to prevent their collapsing inward when a 110 vacuum occurs. The external straps 9, 10 115 will generally provide a sufficient reinforce- 120 ment against pressure within the chamber.

According to Fig. 7 the chamber is made of two heavy sheets 22 with flanges 23 at their 125 edges which are butt welded by the electric 130 resistance method or soldered, brazed or 135 welded in other ways.

According to Fig. 8, the opposite plates 140 24 have at their edges transverse flanges 25 and longitudinal flanges 26 which can be 145 united by common spot welding or similar 150 methods or by the method of Fig. 11 or in any 155 of the ways previously described, or even 160 by fasteners passing through the flanges 26.

In fact they can be economically united in 165 the manner of Fig. 10 in which one of the 170 flanges 26 has an extension 27 which is 175 crimped over the other as in making cans and 180 similar articles.

Where the walls are so thin in proportion 185 to their height and length as not to have the 190 desired rigidity, this quality may be sup- 195 plied by internal braces such as those of Fig. 200 6 or by forming indentations 28, Fig. 9, in 205 the opposite walls 29, which provide internal 210 projections engaging each other in the man- 215 ner of the webs 3 of Fig. 4 and properly 220 distributing any internal strain due to vac- 225 um.

In making the chamber of sheets, various 230 metals may be used such, for example, as 235 steel, copper, brass, aluminum, zinc and al- 240 loys thereof. The thickness will be such as 245 to secure rigidity, so that the walls will hold 250 their shapes and will make good contact with 255

the extended area structure throughout substantially the length and breadth of the contacting portions of the latter.

Various modifications in detail and in the arrangement of the parts may be made by those skilled in the art without departing from the invention as defined in the following claims.

I claim:

10 1. A convection radiator comprising a high, narrow, substantially rigid chamber for steam or other heating medium and an extended area structure applied to the side faces thereof with a good heat conducting contact and providing a number of comparatively small high passages in which the air is heated and circulated so as to carry off the heat rapidly and distribute it into remote portions of the room, said structure extending vertically beyond the chamber a distance at least as great as its lateral extension from the side of the chamber.

2. A convection radiator comprising a substantially rigid chamber for steam or other heating medium and an extended area structure applied thereto with a good heat conducting contact and extending above the same and providing a number of comparatively small high passages in which the air is heated and circulated so as to carry off the heat rapidly and distribute it into remote portions of the room, said extended area structure comprising corrugated sheet metal with the inner portions of the corrugations in contact with the rigid side walls of the chamber and comparatively stiff straps applied to the outside faces of said inner portions of the corrugations and extending substantially to the upper edges of the sheet to hold the latter in place and to stiffen the portion thereof above the chamber.

3. A convection radiator for heating the air of a room, said radiator comprising a high narrow chamber having flat outer faces and having walls so thick as to ensure substantial rigidity against the pressure of steam within and to prevent substantial distortion of such faces and an extended area structure applied to said flat outer faces with a good heat conducting contact and forming a number of comparatively small high vertical passages in which the air is heated and an upward draft induced so as to carry off the heat rapidly and distribute it into remote portions of the room, said extended area structure comprising laterally finned pieces of comparatively thin metal engaging the opposite faces of the chamber and fastened to each other above and below the chamber.

4. A convection radiator for heating the air of a room, said radiator comprising a high narrow chamber having flat outer faces and having walls so thick as to ensure substantial rigidity against the pressure of steam within and to prevent substantial distortion of such

faces and an extended area structure applied to said flat outer faces with a good heat conducting contact and forming a number of comparatively small high vertical passages in which the air is heated and an upward draft induced so as to carry off the heat rapidly and distribute it into remote portions of the room, said extended area structure comprising pieces of sheet metal having inner portions in contact with the side faces of the chamber and having vertical fins extending outward from said inner portions, comparatively stiff straps applied to the outside faces of said inner portions and serving to hold them flat against the faces of the chamber.

5. A convection radiator comprising a chamber for steam or other heating medium and an extended area structure applied to the side faces thereof with a good heat conducting contact and providing a number of comparatively small vertical passages in which the air is heated and circulated so as to carry off the heat rapidly, said chamber having generally flat side walls, the opposite walls having inward projections registering with each other and meeting within the chamber to form transverse braces.

6. A convection radiator comprising a chamber for steam or other heating medium and an extended area structure applied to the side faces thereof with a good heat conducting contact and providing a number of comparatively small vertical passages in which the air is heated and circulated so as to carry off the heat rapidly, said chamber having two generally flat opposite side walls with indentations therein which form internal projections from said opposite sides engaging each other within the chamber.

7. A convection radiator comprising a chamber for steam or other heating medium and an extended area structure applied to the side faces thereof with a good heat conducting contact and providing a number of comparatively small vertical passages in which the air is heated and circulated so as to carry off the heat rapidly, said chamber comprising generally flat side plates with inwardly extending peripheral flanges united to each other.

8. A convection radiator comprising a chamber for steam or other heating medium and an extended area structure applied to the side faces thereof with a good heat conducting contact and providing a number of comparatively small vertical passages in which the air is heated and circulated so as to carry off the heat rapidly, said chamber comprising generally flat side plates with inwardly extending peripheral flanges united to each other and with indentations therein.

9. A convection radiator comprising a chamber for steam or other heating medium and an extended area structure applied to the side faces thereof with a good heat conducting

- contact and providing a number of comparatively small vertical passages in which the air is heated and circulated so as to carry off the heat rapidly, said chamber comprising generally flat side plates with inwardly extending peripheral flanges united to each other and with indentations therein which form opposite internal projections engaging each other within the chamber.

10 10. A convection radiator comprising a chamber for steam or other heating medium and an extended area structure applied to the side faces thereof with a good heat conducting contact and providing a number of comparatively small, vertical passages in which the air is heated and circulated so as to carry off the heat rapidly, said chamber having two generally flat opposite side walls with integral indentations extended inwardly to the opposite wall and serving to hold said flat walls duly spaced and against lateral distortion.

15 11. A convection radiator comprising a chamber for steam or other heating medium and an extended area structure applied to the side faces thereof in intimate heat conducting contact and providing a number of comparatively small, vertical passages in which the air is heated and circulated so as to carry off the heat rapidly, said chamber having two corresponding opposite generally flat side walls with indentations extending inwardly from opposite sides of each chamber to the opposite wall and serving to hold said flat walls duly spaced and against lateral distortion.

20 12. A convection radiator comprising a chamber for steam or other heating medium and an extended area structure applied to the side faces thereof in intimate heat conducting contact and providing a number of comparatively small, vertical passages in which the air is heated and circulated so as to carry off the heat rapidly, said chamber having two corresponding opposite generally flat side walls with indentations extending inwardly from opposite sides of said chamber to the opposite wall and co-operating therewith to hold said flat sides duly spaced at a plurality of separated places.

25 13. A convection radiator comprising a chamber for steam or other heating medium and an extended area structure applied to the side faces thereof with a good heat conducting contact and providing a number of comparatively small, vertical passages in which the air is heated and circulated so as to carry off the heat rapidly, said chamber having inlet and outlet openings and having two corresponding side walls which are substantially flat along the length of their inner faces, and having longitudinal spacing means dividing the interior into a plurality of longitudinally extending passages enclosed between the side walls and the spacing means and com-

30 35 40 45 50 55 60 65 70 75 80 85 90 95 100 105 110 115 120 125 130

14. A convection radiator comprising a chamber for steam or other heating medium and an extended area structure applied to the side faces thereof with a good heat conducting contact and providing a number of comparatively small, vertical passages in which the air is heated and circulated so as to carry off the heat rapidly, said chamber having two opposite side walls which are substantially flat along the length of their inner faces, and having longitudinal spacing means extending across the interior and dividing the interior into a plurality of longitudinally extending passages enclosed between the said walls and the spacing means and communicating with one another only at points beyond said spacing means.

15. A convection radiator comprising a chamber for steam or other heating medium and an extended area structure applied to the side faces thereof with a good heat conducting contact and providing a number of comparatively small, vertical passages in which the air is heated and circulated so as to carry off the heat rapidly, said chamber having two opposite side walls with flat inner faces, and having spacing means between which are vertical passageways enclosed between said flat walls for the free circulation of the heating medium between the several parts of the chamber.

16. A convection radiator comprising a chamber for steam or other heating medium, said chamber having generally flat side walls with braces extending inwardly therefrom and leaving internal passages for the heating medium, and an extended area structure constituting the exposed sides of the radiator applied to the flat side faces of said chamber with a good heat conducting contact and providing a number of comparatively small vertical passages in which the air is heated and circulated to carry off the heat rapidly, said chamber being imperforate (except for the admission and discharge of the heating medium) and said extended area structure being applied to the chamber by means located entirely outside of the chamber and within the outer face of the extended area structure.

In witness whereof, I have hereunto signed my name.

IRVING T. BENNETT.
